UNITED STATES PATENT OFFICE.

DANIEL KOPS, OF NEW YORK, N. Y.

APPAREL-CORSET.

946,232.

Specification of Letters Patent. Patented Jan. 11, 1910.

Application filed October 19, 1909. Serial No. 523,404.

To all whom it may concern:

Be it known that I, DANIEL KOPS, a citizen of the United States, residing in the borough of Manhattan, city, county, and State of New York, have invented an Improvement in Apparel-Corsets, of which the following is a specification.

The device of my present invention bears a close relation to the devices shown and described in the following Letters Patent heretofore granted to me #798,967, September 5, 1905, #898,749, granted September 15, 1908, #914,732, granted March 9, 1909, and #928,669, granted July 20, 1909; the devices of my invention aiming to more perfectly carry out the objects sought by the devices of the said patents, with particular reference to women with stout figures.

The latest fashion and substantial requirement in apparel corsets, particularly those adapted for use in stout figures, are to inclose the figure below the depth or lower edge of a corset of usual construction so as to obviate the protuberant tendency of the flesh particularly in a standing posture and to cause the fit of outer garments to be smooth and unwrinkled, presenting graceful, tapering lines.

In the device of my present invention there are adjacent parts in use all under tension which in their combined action and relations under the tension of hose supporters, pull directly down upon the corset, at an inclination over the abdomen, downward over the abdomen and around the figure below the corset, having the double function of flattening over the abdomen and supporting or holding up under the same; the latter with a yielding tension having a reducing tendency.

In carrying out my invention, I prefer to employ such inclined tapering and adjustable straps and their skirt extensions as are shown and described in my Letters Patent #798,967 and #928,669, hereinbefore referred to. In this improvement I make the corset very much longer at the front over the abdomen than usual; also using longer steels, but I do not raise the corset on the bosom over the usual low cut form.

I employ at the lower edge of the corset at each side of the front steels, elastic straps preferably inclined connected to the corset at their distant ends to or substantially to the lines of union of the inclined tapering and adjustable straps to the corset body, and

the adjacent ends of these elastic straps may be provided with tabs of fabric and have means for connecting the same together and also preferably to the steels of the corset; 60 their connection with one another providing for lines of tension and their connection to the corset steels providing against the upward tendency of said elastic straps under tension. These elastic straps come beneath the inclined tapering straps and over and below the upwardly cut lower edge of the corset proper, and I prefer to make these elastic straps tapering so that their wider ends come together at the front and their 70 narrow ends come at the points of attachment to the corset. The lines of tension of these elastic straps, furthermore, preferably come below the lines of tension of the inclined tapering straps so that the function of 75 the elastic straps is created along the lines which are below the holding-in lines of tension of the inclined tapering straps.

Hose supporters are connected to the adjacent connecting ends of the elastic straps 80 and other hose supporters are connected to the skirt extension ends of the inclined tapering straps, consequently there are separate lines of inclined tension and downward lines of tension as the result of the hose supporters at the front of the corset, to the corset and to the elastic straps, and other lines of downward tension pulling upon the inclined tapering straps in lines which are substantially parallel but spaced apart from 85 the central lines of tension of the first aforesaid hose supporters, all of which is shown in the drawings and hereinafter more fully described in the specification.

In the drawing, Figure 1 is an elevation 95 at the lower portion of my improved corset showing one of the inclined tapering straps and its skirt extension turned to one side. Fig. 2 in larger size shows an elevation of the immediate central and lower portion of 100 this corset as laid out flat. Fig. 3 in larger size is a section approximately on the dotted line w, w , of Fig. 2. Fig. 4 is a substantial vertical section on the dotted line y, y , of Fig. 2. Fig. 5 is a diagrammatic view representing the general relation of the features of my improvement to the human figure so as to illustrate more perfectly the functions performed thereby, and Fig. 6 is a plan view of one of the elastic straps separate as hereinafter described.

In Figs. 1 and 2 of the drawings, a, a

represent the fabric body of the halves of the corset, *b b* the front steels provided with usual fastening devices. *c* are the usual front gores and *d* the usual bone pockets shown in dotted lines in Fig. 1. *e* represents the inclined tapering straps and *f* the skirt extensions or prolongations thereof as in my Patent #998,669. As also shown in the said patent, *2* are eyelets in the free ends of the straps *e* and *3* are posts secured in the front steels of the corset and adapted in the adjustable relation of the straps to engage any one of the eyelets. *g h* represent skirt extensions also similar to those shown in my Patent #928,669; *4* representing an approximate imaginary line of division between the corset body and the skirt extension; said skirt extension in practice being from four to four and a half inches in depth. The lower forward ends of the skirt extensions *g h* are secured to the lower ends of the skirt extensions *f* of the straps *e* by lines of sewing which also connect the said parts of the hose supporter straps *m m*. Other hose supporter straps *l l* are connected to the lower end of the fabric body of the corset directly below the front steels.

As hereinbefore stated, the steels in the corset of my invention are very much longer than they have been heretofore employed, so that the corset of my improvement comes low on the figure over the abdomen and the lower edges of the gores *c* are curved upward as shown by the dotted lines Fig. 2; and in the corset of my present invention, I employ inclined elastic straps *i k* which are preferably tapering. The respective distant ends are preferably provided with tab forms of fabric and the said ends at *5* are connected with the corset at the union of the inclined tapering straps *e* with the body *a* and the adjacent ends of the straps *i k* which come over the corset steels are also preferably provided with tab ends *i¹ k¹* of fabric, which are of appreciable dimensions. The fabric body of the corset is continued quite appreciably below the lower ends of the front steels *b*.

The upper portions of the tab ends *i¹ k¹* are provided with eyelets *6* and the steels adjacent to these eyelets with posts *7*; thus providing an adjustable relation with the two eyelets of each tab with the said posts.

I provide rivets *8* in pairs which pass through the tab ends *i¹ k¹* near their lower parts or below the center and through the fabric body of the corset, and hook members preferably of wire are securely fastened in place by these rivets. These hook members *i* are interlocking and help to hold together not only the adjacent tab ends *i¹ k¹* but the adjacent ends of the corset at the front portions below the steels. These tab ends are also connected to the lower ends

of the corset body below the front steels by the lines of sewing *10* which come at the upper ends of the hose supporter straps *l l* and also assist in securing said hose supporter straps to the fabric body of the 70 corset.

The inclined elastic straps *i k* are preferably tapered and the taper is preferably quite pronounced. These straps may be of plain elastic or they may preferably be of 75 elastic portions with non-elastic end portions as shown and described in the re-issued Letters Patent granted to Kops Bros. as the assignees of Samuel Kops, the one dated May 25th, 1909, and numbered 12962 and the 80 other dated June 8th, 1909, and numbered 12972.

Fig. 1 illustrates the straps *i k* as made of usual elastic with tab ends. Fig. 2 illustrates the straps *i k* of elastic and non-elastic 85 parts as per said re-issued patents, while Fig. 6 illustrates one of the said straps as made without tab ends and entirely of an elastic part 16 and non-elastic parts 17, 18, the ends 17 18 being non-elastic: the narrower end to be sewed to the corset and the wider end to receive the eye-lets 6 and the rivets 8 which secure one of the hook members thereto. I prefer to bind this wide non-elastic end with a tape to keep the same 95 from fraying in use.

In Fig. 1 I have shown a dotted line *11*, a dotted line *12* at substantially right angles thereto, another dotted line *13* and still another dotted line *14*. The dotted lines *11* 100 and *12* indicate the lines of tension of the inclined tapering straps *e* and skirt extensions *f* in connection with the hose supporter straps *m*. The dotted line *13* represents the line of tension of the inclined elastic straps *i k* as between their place of union at the connection *5* to the corset body and the point of connection of their forward ends to one another and to the corset, and the vertical dotted line *14* represents the downward pull 110 or tension of the hose-supporter straps *l* in a substantially vertical direction; the dotted line *12* also being the downward line pull or tension as against the line *11* drawn through the sides of the corset over the figure and the fastening hook *3*, and the dotted line *15* in Fig. 5 diagrammatically represents a body line of section to show the fit of the corset and the parts connected therewith also in illustration of the functions of 120 the parts.

From the foregoing description, the illustration and the dotted lines of tension, it will be apparent that there are separate and independent downward pulling lines of tension as the result of the connection of hose supporters, and also that there are separate and independent inclined lines of tension pulling around the corset over the abdomen; that the line of tension *13* indicates the effect 130

of the elastic member, the tension of which together with the position shown in Fig. 5, demonstrate an abdominal support or holding-up function while the line of tension 11 5 of the inclined tapering strap members also indicates an abdominal compression or holding function above that produced by the inclined elastic member and certain tension coupled with the substantially vertical lines 10 of tension 12 and 14 indicate a further effect of flattening of said lines of tension, conspiring for the production of a supporting function and flattening front effect.

I claim as my invention:

15 1. An apparel corset combining with the fabric body halves thereof, strap members in independent pairs across the lower front portion of the corset disconnected from each other from their places of attachment to the 20 corset and adapted for separate lines of tension having supporting and flattening functions, and independent hose supporter devices in pairs secured thereto and adapted for separate downward lines of tension having 25 supporting and flattening functions.

2. An apparel corset combining with the fabric body halves thereof, strap members in independent elastic and non-elastic pairs across the lower front portion of the corset, 30 disconnected from each other from their places of union with the corset and both pairs adapted for separate lines of tension having simultaneous supporting and flattening functions, and hose supporter devices in 35 pairs connected thereto and adapted for separate downward lines of tension having supporting flattening functions.

3. In an apparel corset, the combination with the fabric body halves, of inclined elastic straps overlying the lower edge of the 40 corset at the front, at their distant ends connected to the corset body, means for remov-

ably connecting parts of their juxtaposed ends and for adjustably connecting other parts of their ends.

4. In an apparel corset, the combination with the fabric body halves, of inclined elastic straps overlying the lower edge of the corset at the front, at their distant ends connected to the corset body, means for connecting their juxtaposed ends, means for suitably securing the lower portions of said ends to the fabric body below the steels, means for adjustably connecting the upper part of said ends to the corset and means for applying a downward tension to the said straps at their place of connection.

5. In an apparel corset, the combination with the fabric body halves and long steels, of inclined elastic straps adjacent to the lower edge of the corset at the front, at their distant ends connected to the corset body, means for connecting together their juxtaposed ends, means for adjustably connecting said ends to the corset body, means for applying a downward tension to the said straps at their places of connection, inclined tapering non-elastic straps with depending skirt extensions, the latter straps secured along distant ends to the fabric body of the corset and occupying a position higher up on the corset than the elastic straps, means at the free ends of said inclined tapering straps for connecting the same in an adjustable relation to the corset at the front 70 steels and means connected to the lower ends of the skirt extensions for applying a downward pull and tension.

Signed by me this 15th day of October, 1909.

DANIEL KOPS.
